UNITED STATES PATENT OFFICE.

HENRY H. VAUGHAN, OF MONTREAL, QUEBEC, CANADA.

DRYING ROLL FOR PAPER-MAKING MACHINERY.

Application filed April 3, 1920. Serial No. 371,059.

To all whom it may concern:

Be it known that I, HENRY H. VAUGHAN, a subject of the King of Great Britain, and resident of the city of Montreal, Province 5 of Quebec, Dominion of Canada, have invented certain new and useful Improvements in Drying Rolls for Paper-Making Machinery; and I do hereby declare that the following is a full, clear, and exact description thereof.

My invention relates to machinery for drying paper, mill board and the like in which paper or mill board is carried around a number of drums heated by steam or other 15 suitable means and is held in position upon the drums during travel around the same by suction.

My invention consists of the particular construction and arrangement of parts hereinafter described and pointed out in the claims.

For full comprehension, however, of my invention reference must be had to the accompanying drawings in which similar 25 reference characters indicate the same parts and wherein:

Figure 1 is a side elevation partly in longitudinal section of a dryer roll constructed according to my invention;

Figure 2 is a transverse sectional view taken on line 2—2 Fig. 1;

Figure 3 is a sectional view taken on line 3—3 Fig. 1;

Figure 4 is a detail fragmentary sectional 35 view of the valvular means controlling suction through the periphery of the roll;

Figure 5 is a detail elevation of one of the valvular members; and

Figures 6, 7 and 8 are detail views of the 40 means for clamping the valvular member in position.

In the embodiment illustrated each drum of my improved drying means consists of a hollow cylindrical member 2 the ends of 45 which are closed by covers 3 and 4 the cylindrical portion of the drum being perforated throughout its length as at 5 the perforations being arranged in circumferential series. The drum is mounted in standards 50 6 by means of trunnions 7 and 8 formed integrally with the covers the trunnion 7 being bored axially to accommodate the pipe (not shown) for supplying the steam or other heating medium to the interior of the 55 drum and for the exhaust of the condensation water.

A plurality of longitudinal tapered pipes 9 are arranged in circumferential series and each is connected to the perforations 5 immediately adjacent by means of short branch 60 radial pipes 10. These longitudinal pipes extend from their tapered ends in close proximity to the cover 3 to a spider adjacent to cover 4, the hub of the spider being constituted by an inward extension of 65 trunnion 8 and radial pipes 13 the outer end of each of which is connected to one of the pipes 9. Suction through perforations 5, pipes 10 and longitudinal pipes 9 is caused by a suction device illustrated diagrammatically at 14 which is connected thereto by a valve-controlled pipe line 15. The valvular mechanism controlling communication between this pipe line and the pipe system within the drum consists of 70 two valvular members, one member being constituted by the trunnion 8 which is rotatable in unison with the drum. This trunnion has a series of longitudinal passages 16 in spaced annular arrangement in 75 cross section and extending from end to end of the trunnion and having their inner ends in communication with the pipes 13 their opposite ends being adapted to communicate with a valve chamber 17 within 80 the valve casing 18. This second valve member is held against rotation by a clamp 19 which straddles one of a pair of elongated bolts 20 screwed into the machine frame. These bolts constitute part of the 85 means for maintaining the fixed valve member in bearing relation with the outer end of the trunnion 8 such means also including a saddle plate 21 carried by the bolts and encircling the pipe line 15 and a helical 90 spring 22 bearing between the saddle plate and the valve member 18 and encircling the pipe line 15. The valve chamber in the member 18 is of semicircular form and is adapted to effect communication between a 95 plurality of the passages simultaneously; the number which will communicate will, however, depend upon the extent of the area through which suction is to take place. As the point at which the paper goes on and 100 leaves the drum is determined by the position of the latter in the machine, and as suction should take place immediately before and after the paper goes on and leaves the drum, respectively, it is necessary to 105 provide for adjustment of the fixed valvular member relatively to the other valvular 110

member. This is permitted by slots 23 in the clamp 19 which accommodate clamping screws 24 which are screwed into the fixed member 18.

5

Operation.

As the drum rotates it carries with it trunnion 8 and the longitudinal pipes 9 with branch pipes 10 and 13. Suction devices having been set in motion a vacuum is maintained in the valve chamber 17 and as rotation continues the passages 16 will successively come into communication with the valve chamber thereby causing suction 15 through pipes 13 communicating with said passages pipes 10 and their respective perforations. Communication between the passages 16 and valve chamber should take place slightly in advance of the point at 20 which the paper goes on the drum and such communication should continue until immediately after the paper leaves the same.

What I claim is as follows:

1. In paper making machinery the combination with a rotary hollow perforated drum for drying paper and the like, said drum having an opening for admitting a heating medium to its interior, of means for causing suction through said perforations for the 25 purpose of maintaining the paper to be dried in position upon the periphery of drum while in contact with the latter, said means consisting of a suction pipe line, a plurality of pipes within the drum extending longitudinally of the same, a plurality of branch pipes effecting communication between each of the longitudinal pipes and the perforations, and valvular means connecting said longitudinal pipes to the suction 30 pipe line, such valvular means consisting of a stationary member and a member rotatable in unison with the drum and coacting with the stationary member.

2. In paper making machinery the combination with a rotary hollow perforated drum for drying paper and the like, said drum having an opening for admitting a heating medium to its interior, of means for causing suction through said perforations for 45 the purpose of maintaining the paper to be dried in position upon the periphery of drum while in contact with the latter, said means consisting of a suction device, pipes extending longitudinally within the drum 50 and arranged in circumferential series, a plurality of branch pipes effecting communication between each of the longitudinal pipes and the perforations in the drum, means effecting communication between the longitudinal pipes and the suction device, said means including a valvular member rotatable in unison with the drum and consisting of a trunnion on one end of the drum 55 and containing a plurality of passages to 60 which said longitudinal pipes are connected,

and a stationary valvular member controlling said passages.

3. In paper making machinery the combination with the machine frame and a hollow perforated drum for drying paper and the like, of means for causing suction through 70 said perforations said means consisting of a suction device, pipes extending longitudinally within the drum and arranged in circumferential series, a plurality of branch 75 pipes effecting communication between each of the longitudinal pipes and the perforations in the drum, means effecting communication between the longitudinal pipes and the suction device, said means including a 80 valvular member rotatable in unison with the drum and consisting of a trunnion on one end of the drum and containing a plurality of passages to which said longitudinal 85 pipes are connected, and a stationary valvular member controlling said passages; means for yieldingly maintaining said stationary member against the outer end of the trunnion, said means consisting of a saddle plate, bolts securing said plate to the 90 machine frame, and a spring bearing between said plate and stationary valvular member, and means for preventing rotation of said stationary member, and permitting of adjustment of the member for the purpose of advancing or retarding the point at which communication between the suction device and the passages is effected.

4. In paper making machinery the combination with a rotary hollow perforated drum 100 for drying paper and the like said drum having an opening for admitting a heating medium to its interior; of means for causing suction through said perforations for the purpose of maintaining the paper to be 105 dried in position upon the periphery of drum while in contact with the latter; said means consisting of a suction pipe line, a plurality of pipes within the drum extending longitudinally of the same, a plurality 110 of branch pipes effecting communication between each of the longitudinal pipes and the perforations, and valvular means connecting said longitudinal pipes to the suction pipe line, such valvular means consisting of a stationary member and a member rotatable in unison with the drum and coacting with the stationary member, one of said members being adjustable for the purpose of advancing or retarding the point at 115 which communication between the suction device and the longitudinal pipes is effected for the purpose set forth.

In testimony whereof I have signed my name to this specification in the presence of 125 two witnesses.

HENRY H. VAUGHAN.
